(57) **CLAIM**

The ornamental design for a mobile phone holder as shown and described.

DESCRIPTION

FIG. 1 is a perspective view of a mobile phone holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mobile phone holder where the mobile phone holder is in a first configuration of use;

FIG. 10 is a perspective view of the mobile phone holder where the mobile phone holder is in a second configuration of use;

FIG. 11 is a perspective view of the mobile phone holder where the mobile phone holder is in a third configuration of use;

FIG. 12 is a perspective view of the mobile phone holder where the mobile phone holder is in a fourth configuration of use; and,

FIG. 13 is a perspective view of the mobile phone holder where the mobile phone holder is in a fifth configuration of use.

The broken lines in the drawings depict portions of the mobile phone holder, and the rest broken lines merely shown in FIGS. 9-13 are directed to the environment. All the broken lines form no part of the claimed design.

1 Claim, 13 Drawing Sheets
